EXPANDING MOUTH FILTER FOR SUCTION
CLEANING DEVICESUncas A. Whitaker, Harrisburg, Pa., assignor to
The Hoover Company, North Canton, Ohio, a
corporation of Ohio

Application June 22, 1951, Serial No. 233,020

10 Claims. (Cl. 183—51)

1

My present invention relates to the art of suction cleaning devices and in particular to filtering devices for such cleaners.

Floor supported and handle propelled suction cleaners are customarily provided with a filter which extends from the cleaner exhaust outlet on the cleaner body outwardly and rearwardly of the propelling handle and has its upper end resiliently supported by the propelling handle adjacent the hand grip thereof. After a period of use, such filters become dirt filled and must be emptied. It is customary emptying procedure to remove the bag from the exhaust outlet of the cleaner and then to empty the same through a large closable opening at the upper end of the filter bag. This construction necessitates a bag which is open at each end, is provided with closing means for the wide mouth thereof at the upper end and a means of securing the same to the cleaner exhaust outlet at the lower end. It is not generally feasible to empty the filter through the inlet mouth thereof which must conform to the necessarily restricted exhaust port of the cleaner.

It is a particular object of my invention to provide a filter bag for suction cleaners having a permanently closed upper end and a lower end openable to the full diameter of the bag and readily closable to form a small diameter mouth engageable with a conventional exhaust port on a suction cleaner.

The present invention provides a filter for a suction cleaner having a permanently closed upper end and a lower end which is openable to the maximum extent provided by the bag material and readily closable to form an inlet which may be applied to the exhaust port of a conventional suction cleaner. The inlet mouth of the bag is provided with a frame structure which serves to seal the inlet mouth of the bag to the suction cleaner exhaust port, to secure the filter bag to the exhaust port mechanically, and to avoid excessive gathering of the material of the bag to reduce the same to the size of the cleaner exhaust port. The filter is folded on itself at points which will not engage the cleaner exhaust port but which do reduce the circumference of the bag mouth to a small value sufficient to fit upon the cleaner exhaust port. The same means are utilized to clamp the foldable mouth structure of the filter in folded position and to secure and seal the same to the cleaner exhaust port. My present construction provides a means for gathering the bag to make the same fit the conventional small size exhaust port of a suction cleaner without necking in the bag at this

2

point to form a restricted lower end characterized by the provision of a large number of unsightly, dirt trapping pleats which also reduce the dirt storage capacity and filtering area of the filter.

Other objects and advantages of the invention will become apparent as the description proceeds when taken in connection with the accompanying drawings in which:

10 Figure 1 is a side elevational view of a suction cleaning device having a part thereof broken away and shown in section on an enlarged scale to illustrate a filter mounting and exhaust port;

15 Figure 2 is a bottom view of the filter attached to the exhaust port of a suction cleaner;

Figure 3 is a perspective end view of a filter for suction cleaners in partly folded condition;

Figure 4 is a perspective view of a filter mouth frame shown in expanded condition; and

20 Figure 5 is a partial bottom view of the filter frame in folded condition.

Referring now to the drawings in detail and first to Figure 1 thereof, there is illustrated a suction cleaner indicated generally by the reference character 1 embodying the usual suction nozzle 2 and supported upon wheels 3. A propelling handle 4 is pivotally attached to the body 1 by conventional means not shown. The cleaner is provided with an exhaust duct 6 terminating in a substantially circular outlet mouth 7 inclined to the horizontal as shown to face slightly upwardly and rearwardly of the cleaner body 1. The exhaust port 7 is surrounded by a channel 8 formed between the spaced flanges 9 and 10 projecting outwardly from the exterior surface 35 of the exhaust duct 6. A filter 11 is secured to the exhaust duct 6 in the seat 8 in a manner to be described hereinafter. The upper end of the filter is permanently closed as by stitching and is secured to a plate 12 to which is attached a supporting spring 13 secured at its upper end to a hook 14 carried by the upper end of the propelling handle 4.

The filter 11 is preferably constructed of textile material of a fine mesh suitable for filtering fine dirt from the dirt laden air stream discharged from the cleaner through the exhaust duct 6. The lower end of the filter 11 is telescoped over a folding mouth frame indicated generally by the reference character 17. The material of the filter is then folded inwardly around the frame 17 and stitched to itself as at 18 to form a hem encasing the folding frame 17.

The frame 17 is illustrated generally in the perspective view of Figure 4 and is constructed of 55 thin section sheet metal stock. The frame 17 is

composed of a pair of identical opposed members 20—20a positioned in face-to-face relation and joined at their ends by folding hinge structures 21—21a respectively. The principal members 20 and 20a are identical and only the member 20 will be described in detail; corresponding reference characters are applied to corresponding portions of the member 20a distinguished by the addition of the subscript "a." The principal member 20 comprises a half-round collar section 22 having parallel projecting flanges 23 extending a short distance beyond the ends thereof. Each flange 23 is joined to a parallel side arm portion 24 by means of a step section 25 which positions the arms 24 away from the flanges 23 in the direction of the bight portion of the collar 22. The arms 24 are aligned with each other and parallel to the aligned flanges 23.

The folding hinge structures 21 each connect a corresponding pair of opposed side arms 24—24a. Since the hinges 21—21a are identical with each other, only the hinge 21 will be described and corresponding reference characters are applied to corresponding parts of the folding hinge 21a distinguished by the addition of the subscript "a." The hinge structure 21 comprises a hinge leaf 27 hingedly joined to the end of the arm 24 by a hinge pin 28. The other end of the hinge leaf 27 is joined to a hinge leaf 29 by means of a hinge pin 30. The hinge leaf 29 is then hingedly connected to the side arm 24a by a hinge pin 31.

Figure 4 illustrates the frame structure in its maximum open position. The frame structure assumes the position illustrated in Figure 5 when folded by moving the hinges 30—30a inwardly towards each other. Only one end of the folded frame structure is shown in Figure 5, it being understood that the opposite end assumes an identical relationship and that the collars 22—22a are brought together as shown in Figure 5 to form a substantially continuous band. As shown in Figure 5, the hinge leaves 27 and 29 fold into juxtaposed parallel relationship to bring the hinges 28 and 31 adjacent each other and to position the hinge 30 in the space provided between the step sections 25—25a of the principal side members. It is apparent from this figure also that the flanges 23—23a abut in juxtaposed relationship between the hinge 30 and the adjacent ends of the collars 22—22a.

Figure 3 illustrates the mouth portion of the completed filter structure in partially folded condition. The frame 17 is enclosed in the hem 18 in the construction of Figure 3 and is invisible; however, portions of the filter mouth in Figure 3 are designated by reference characters applied to corresponding portions of Figure 2 in order to identify the relationship and position of the frame structure in the completed filter.

A U-shaped spring clip 33 is pivotally attached to each arm 24a by means of a rivet 34 after assembly of the frame 17 with the filter 11. The mounting of the spring clips 33 is such that they are freely pivotal from the released position illustrated in Figure 3, and in dotted lines in Figure 2, to the clamping position illustrated in full lines in Figure 2.

It is apparent, from Figures 3 and 5, that the fabric surrounding the frame 17 is brought into juxtaposed relation to form seals between the members 24 and 27, 27 and 29, and 29 and 24a. Similarly, the fabric forms seals by being pressed between the hinge 30 and the facing shoulder portions 25—25a in the completely folded con-

dition of the apparatus. The flanges 23—23a are also brought into juxtaposed relation to cause the fabric to form a seal therebetween. The spaces between the above mentioned elements 5 illustrated in Figure 5 are proportioned to accommodate slightly less than two layers of fabric so that the strips of filter fabric extending around facing portions of the frame 17 are pressed together in the folded condition of that frame. 10 When the apparatus is in the folded condition illustrated in Figures 2 and 5, the U-shaped spring clips 33 are swung down to the full line position illustrated in Figure 2 whereby they engage over the outer faces of the arms 24 and 24a forcing the same firmly towards each other and into engagement with the hinge leaves 27 and 29 which are also forced together to seal the fabric. This action also brings the flanges 23—23a together to cause the fabric thereon to press together to 15 form a seal at this point.

The collar portions 22—22a of the frame are sized to fit snugly in the channel 8 between the flanges 9 and 10. When the filter mouth is folded, as illustrated in Figures 2 and 5, and brought 20 into engagement with the channel 8, the spring clip 33 firmly presses the folded portions of the filter frame into engagement with each other and tension the collar sections 22—22a against the inner surface of the channel 8 to form an air seal 25 at this point. The spring clip forms an air seal between the folded portions of the mouth frame structure, an air seal between the collars 22—22a and the channel 8, and mechanically anchors the filter to the cleaner exhaust port. This arrangement dispenses with clamps or other structures formed on the cleaner body proper and incorporates these functions into parts of the filter which also serve to clamp such sections of the filter into a predetermined assembled relationship.

The present frame construction provides a device which folds readily into a size to fit a normal cleaner exhaust port but which is openable to provide an extremely wide mouth for the cleaner bag to facilitate emptying the same of accumulated dirt. By folding portions of the bag into laterally extending side wings with respect to the cleaner exhaust port, excessive necking in of the filter at the bottom portion thereof is completely avoided and a pleasing appearance is provided by the longitudinally extending side folds or pleats formed in the bag and running from the hinge leaf sections 27 and 29, and 27a and 29a. This arrangement provides a large dirt pocket at the bottom portion of the filter structure within which accumulated dirt may gather without blocking the exhaust port for the cleaner or otherwise interfering with the sufficiency of the filter as such. This action may be facilitated by tailoring the fabric of the filter to form a pocket as indicated at 36 in Figure 1. This arrangement provides the filter with a very large dirt capacity in a manner which will not tend to clog the cleaner exhaust outlet or to reduce significantly the effective filtering area available to the structure.

The above described construction has been found to provide a filter structure characterized by great ease of emptying the same due to the large emptying mouth provided by the frame structure which folds readily to define a small size inlet mouth which will fit the small size exhaust port customarily provided on suction cleaner body structures.

I claim:

1. A filter for suction cleaners comprising a tubular body of filter material having a perma-

nently closed end and an open end, a foldable frame secured to the open end of said filter comprising a pair of opposed principal members each having inlet mouth forming portions provided with projecting side arms, foldable members connecting the ends of corresponding side arms and foldable between said side arms outwardly of said mouth forming portions to bring said mouth forming portions together.

2. Apparatus according to claim 1 including clamping members carried by the side arms of one of said principal members for clamping the corresponding side arms of each of said principal members together with one of said foldable members positioned between each of said pairs of corresponding side arms.

3. A suction cleaner comprising a body member having an exhaust duct terminating in an exhaust port, means forming a channel around said duct adjacent said exhaust port, a tubular filter member having an open end and a permanently closed end, a mouth frame secured to the open end of said filter member and composed of a pair of opposed principal members lying in said channel and each embracing one-half the circumference of said duct, side arms projecting laterally from the ends of each of said principal members, folding hinge members each hingedly connected to the ends of a corresponding pair of said side arms and folded inwardly therebetween, and clamping means carried by one side arm of each of said corresponding pairs engaging the other side arm to clamp said side arms and the hinge members therebetween in air tight relation and to clamp said principal members in said channel.

4. Apparatus according to claim 3 in which said side arms have base portions directly joined to said principal members with the base portions of corresponding side arms in abutting relation and projecting portions offset from said base portions to provide space to receive said folding hinge members outwardly of said principal members.

5. A filter comprising a tubular body of filter material having an open end and a closed end, a mouth frame secured in the open end of said tubular body comprising a pair of opposed principal members, each of said principal members comprising a flat strip having a pair of abutment surfaces offset from the plane of said strip and lying in a common plane, said abutment surfaces being spaced from the ends of said strip and each other, and a central collar portion connecting the adjacent ends of said abutment surfaces and extending across the plane of said strip in a direction opposite to the direction in which said abutment surfaces are offset from said strip, a pair of foldable hinge members each having its ends hingedly joined to corresponding ends of said principal members, said hinge members being foldable between said principal members with their inwardly projecting ends lying outside said collar portions and adjacent said abutment surfaces to bring said abutment surfaces into

engagement to form an inlet mouth defined by said collar portions.

6. A mouth frame for suction cleaner filters comprising a pair of opposed flat strip members each having a central collar section offset away from the opposed flat strip member, a pair of opposed foldable members, and means hingedly joining the ends of each of said foldable members to a pair of corresponding ends of said flat strip members to close said frame.

7. Apparatus according to claim 6 in which each of said flat strip members includes sections at its junction points with said collars offset in the direction of the opposed flat strip member to provide abutments engageable to space the corresponding end portions of said flat strip members to accommodate said foldable members in their folded condition.

8. A filter for suction cleaners comprising a tubular body of filter material closed at one end and having an open end, a frame secured to said tubular body in the open end thereof, said frame comprising a pair of opposed principal members each having flat coplaner end portions joined to a central collar portion offset from the plane of the end portions in a direction away from the opposed principal member adapted to form an inlet mouth to said tubular body when said principal members are brought together, a pair of opposed foldable members, means hingedly joining the ends of each of said foldable members to corresponding ends of said principal member to close said frame, said foldable members each being foldable between the end portions of said principal members to which they are attached outwardly of said collars.

9. Apparatus according to claim 8 in which said principal members each includes a pair of sections at the junctions of said collars and said end portions offset in the direction of the opposed principal member forming abutments spacing said end portions to accommodate said foldable members and sealing the infolded ends of said foldable members when said abutments are engaged with each other.

10. Apparatus according to claim 8 including U-shaped clamping members movably carried by said frame and engageable about each pair of end portions and the infolded foldable member to secure said frame in folded condition.

UNCAS A. WHITAKER.
